UNITED STATES PATENT OFFICE.

LOUIS M. POTTS, OF BALTIMORE, MARYLAND, ASSIGNOR TO THE ROWLAND TELEGRAPHIC COMPANY, OF BALTIMORE, MARYLAND, A CORPORATION OF NEW JERSEY.

TELEGRAPHY.

No. 901,372.

Specification of Letters Patent.

Patented Oct. 20, 1908.

Application filed March 9, 1907, Serial No. 361,530. Renewed April 10, 1908. Serial No. 426,316.

To all whom it may concern:

Be it known that I, LOUIS M. POTTS, a citizen of the United States, residing at Baltimore city, in the State of Maryland, have invented certain new and useful Improvements in Telegraphy; and I do hereby declare the following to be a full, clear, and exact description of the invention, such as will enable others skilled in the art to which it appertains to make and use the same.

This invention relates to a method of balancing the lines of electric circuits and particularly to the balancing of the lines employed in duplex systems of telegraphy.

In most systems of telegraphy the messages are transmitted in opposite directions simultaneously. It is necessary that the signals transmitted from the station shall have no effect upon the receiving relay at said station, this relay being controlled entirely by the incoming signals from the distant station. For this purpose an artificial line is employed at the station which is made to have all the electrical characteristics of the real line. A relay having two identical windings is connected to these lines in such a manner that the outgoing current from the transmitting station passes through one winding to the real line and through the other winding in the opposite direction to the artificial line. When the artificial line has been so adjusted that the same amount of current passes through both coils there will be no effect produced by the outgoing current upon the relay.

This method is sometimes modified by substituting for the oppositely wound coils of the relay two equal resistances and connecting a single wound relay across from the beginning of the real line to the beginning of the artificial line. In this case also, when equal and like currents pass through the real and artificial lines there is no effect of the outgoing current upon the relay.

In order to determine when the currents in the real and artificial lines are equal, it is usually the custom to observe the effect of the outgoing signals upon the relay and then to adjust the artificial line until no effect is produced on the relay, or as small an effect as may be necessary to insure good reception.

The present invention furnishes a method of not only indicating when the balance has been obtained between the real and the artificial lines but it also indicates whether any

particular adjustment of the artificial lines is made in the proper direction to make the currents in said lines more nearly alike. It has been customary in some cases to connect the beginning of the real line and the beginning of the artificial line through a galvanometer for the purpose of determining when a balance has been obtained. Such methods, however, do not furnish an exact means of showing the state of the balance, but amount to little more than rendering visible the kicks of the main line relay caused by the reversals of the current.

My invention furnishes a method of indicating when the balance is perfect by means of the indicating needles of electrical measuring instruments of the dynamometer type.

My invention also furnishes a method of indicating the character of the adjustment necessary to produce a balance by indicating separately the capacity adjustment and the resistance adjustment of the line.

Most high speed systems employ reverse current signals, while some employ modified alternating currents. Since any current reversed at intervals may be considered a more or less complicated combination of alternating currents of different phases, frequencies, and amplitudes, and since a simple alternating current furnishes the most convenient and simple method of determining the theory of this method, I shall describe it with reference to a simple alternating current.

The essential feature of this method consists in the employment of, at least, two indicating instruments having electrical fields produced by local means and having movable coils which are in circuit between the beginning of the real line and the beginning of the artificial line and at least one of which instruments has a field produced by the signaling current itself.

In order to more fully describe my invention reference will be had to the accompanying drawings, in which—

Figures 1 to 6 inclusive are diagrams showing the arrangement of circuits which may be employed at a station for the purpose of determining the balance between the real and the artificial lines; and Figs. 7 and 8 are diagrams showing the phase relations of the currents in the several local circuits.

Referring first to the arrangement shown in Fig. 1, M indicates the relay magnet hav-

ing its coils k and k' oppositely wound and connected respectively in the real or main line L and the artificial line or local circuit A which is grounded as indicated at G . The 5 artificial line contains an adjustable resistance R and a condenser C composed of a number of elements c , more or less of which may be connected in circuit for the purpose of adjustment in obtaining a balance. Two 10 indicating instruments of the electro-dynamometer type, having field coils F and movable coils B and D , are pivotally mounted to swing within the influence of said fields and provided with needles or pointers p and p' . It 15 will be observed that the field coils of the instruments are joined in parallel in the transmitting circuit before it reaches the point of divergence E between the real and artificial lines. The movable coils B and D 20 are connected in parallel across from the beginning of the real line to the beginning of the artificial line, a resistance r and a condenser c' being connected respectively in circuit with the coil B and the coil D . In 25 balancing the circuits so that the outgoing current will have no effect upon the relay, the artificial line is adjusted until the two pointers rest at zero on their scales.

The necessity for the use of two indicating 30 instruments will be evident by referring to certain principles which may be better illustrated by referring to the phase diagrams shown in Figs. 7 and 8. Referring to Fig. 7, let the curves l and a represent, respectively, 35 the currents through the real line and the artificial line. The curve s , the sum of l and a , will then represent the current from the transmitting station which flows through the fixed coils F of the instruments. The 40 curve, b , representing the difference between the currents l and a , will indicate the current flowing through the movable coil B except for the amplitude which will depend upon the impedance in series with the coil. The 45 curve d represents the current, except for the amplitude, through the movable coil D , being 90 degrees in phase in advance of the current in the coil B , due to the effect of the condenser c' in circuit therewith. Since the 50 currents in the field coils F and the coil B are in phase, while the current in the coil D is in quadrature with the current in the field coils, a deflection will be indicated by the needle p but no deflection will be indicated by the needle p' . It is evident, 55 therefore, that the pointer p' attached to the coil D could not alone give a correct indication of the equality and similarity of the currents at the beginning of the real and the 60 artificial lines. An exact indication of the currents in the two lines can, however, be obtained by my method which will be better understood by reference to the phase diagram shown in Fig. 8. As before, l and a 65 represent, respectively, the currents at the

beginning of the real line and the beginning of the artificial line. Let it be assumed that the adjustments have been so made that there will be a difference of phase of 120 degrees between these currents. If the two currents 70 are equal in value, s will represent the phase of the current in the fixed coil F of the two instruments and the curve b will represent in phase the difference between l and a , or the phase of the current in the movable coil 75 B . Inasmuch as said curve b is 90 degrees in phase in advance of the current s , it is evident that curve s also represents the phase of the current in the movable coil D .

Now since currents in the coils B and D 80 differ in phase by 90 degrees and since the curve s represents the phase of the current in the fixed field coils and also in the movable coil D , it is evident that there may be a deflection of pointer p' attached to coil D , 85 and there will be no deflection of pointer p attached to coil B . It will be seen from this consideration that the use of the coil B alone would not completely indicate a balance, since zero deflection would simply indicate 90 that the currents in the fixed and movable coils were in quadrature while the currents through the two coils of the relay might differ in value and there might be, therefore, an actual difference of potential 95 at the beginning of the artificial and real lines. In the case considered, the adjustment of the artificial line has been assumed such that the currents represented by curves l and a have equal amplitudes and differ only 100 in phase, but this has been assumed merely for convenience. If these amplitudes had been assumed to be different, there would be a different phase relation of l and a for a phase difference of 90° between s and b . 105 Coil B would indicate zero deflection even when the currents were not alike. There will, therefore, be a varying sensibility of the instruments having the coils B and D respectively as the artificial line is adjusted, depending upon the amplitudes and phase relations of the two currents. However, when one instrument has its maximum sensibility the other has its minimum sensibility. 110

From a consideration of the above examples, it is clear that two instruments are necessary to completely determine the balance between the real and artificial lines for an alternating current. A consideration of the above examples has thus shown that 115 there is a certain relation in which the needle p' gives no indication of an unbalanced condition and again that there may be a condition of values in which the needle p will give no indication of an unbalanced condition. 120 It is clear, therefore, that two instruments are necessary to completely determine the balance between the real and artificial lines for an alternating current. 125

There are various modifications of the ar- 130

arrangement above described for carrying out my invention. In Fig. 2 I have shown the substitution of a reactance or self-induction coil *I*, for the condenser in series with the coil *D*, for the purpose of establishing a difference of phase between the currents in the movable coils of the two instruments. Any arrangement which establishes these phase differences will accomplish in a more or less efficient manner the result desired. In Fig. 3, I show an arrangement in which the fixed coils of each instrument are made in sections exactly alike, one section being connected in the real line and the other in the artificial line. In Fig. 4, I show the fixed coils of the two instruments in a separate circuit or branch from the main circuit fed by the telegraphic transmitter.

I have found that it is not necessary in all cases to employ electro-magnets for the fixed coils of both instruments, but that a permanent magnet may be employed in one of the instruments, as shown at *P* in Fig. 5. It will be apparent that this substitution can be made by considering certain points of great importance in the balancing of the relay for duplex telegraphy.

In sending telegraphic signals, it is usual for the signals to consist of impulses of varying lengths in opposite directions, so that taking any given signals, there is usually a preponderance of current in one direction over that in the other. For instance, in the Rowland system, when no signals are being sent, alternating currents of different frequency are flowing in the line and the signals consist in a reversal of certain combinations in the alternations or half waves. In such systems, there are two different effects of the signal upon the main line relay, one of these being a regular vibration of the relay due to the alternating current, and the other consisting of distinct kicks of the relay due to the reversed half waves. The removal of these so-called kicks in balancing is quite important.

I will now describe how my method affords a means of separating the two effects mentioned, so that one needle indicates the balance due to the regular alternating current, and the other needle indicates the reversal of the kicks; and, furthermore, one needle indicates the balance of the capacity current and the other indicates the balance of the resistance current.

In Fig. 5, the instrument on the left has fixed electro-magnetic coils, as in the preceding figures, while the instrument on the right has its field furnished by the permanent magnet *P*. The two movable coils *B* and *D* are in series with each other and a resistance *r* and are connected across from the beginning of the real line to the beginning of the artificial line. Now if signals are sent which produce a preponderance of current in one

direction there will be a deflection of the needle *p'* of the coil *D*. The artificial line will then be adjusted so that there will be no preponderance of current in one direction over that in the other, as will be indicated when the pointer *p'* indicates zero deflection. The needle *p* of the coil *B* will indicate the presence of an alternating current or reversed impulses. It will be seen that the coil *D* takes the place of the coil *D* in the arrangement shown in Fig. 1, as it furnishes an additional guide in adjusting the line, and indicates an unbalanced line when the conditions are such as to reduce the sensibility of the coil *B*. I have found that the coil *B*, in the arrangement shown in Fig. 5, indicates the capacity adjustment of the line and the coil *D* the resistance adjustment, these indications being practically independent. I have also found that the coil *B* indicates the vibrations of the relay due to the alternating current, and the coil *D* indicates the reversals or kicks due to reversed or modified waves.

In using my instruments in actual practice, I contemplate having a switch mounted upon the instrument, so that in one position the coils will be connected as shown in Fig. 1, with an alternating current supplied to the field magnets, and in the other position of the switch one of the instruments as *D* will be supplied with a constant field, either by a permanent magnet as shown in Fig. 5, or by connecting the field coils to a direct current source. When the switch is in the latter position, the resistance of the artificial line will be adjusted until the needle *p'* indicates zero deflection. The switch is then changed to the first position, and, the resistance remaining unchanged, an adjustment is made in the capacity of the artificial line until the needles of the two instruments indicate zero deflection. By this arrangement one position of the switch will give an indication of the resistance adjustment and the other switch position will give the capacity adjustment by means of the indication obtained from the two needles. Although a fair indication of the capacity adjustment may be obtained by means of one needle, it is more accurate, for the reasons above stated, to take the indications of the two instruments.

In order that the lines may be balanced while signals are being received from the distant station, I may employ the arrangement disclosed in Fig. 6. In this case the indicating instruments are connected in circuit only for a certain interval of time. In systems where the signals transmitted from the two ends of the line are synchronous, it is possible to arrange the commutator segment *H* on one of the synchronously rotating parts, and a corresponding commutator segment on the opposite end of the line, so that the instrument may be connected in circuit at times

when there is no received current and the balance may be obtained by the method above described.

It will be understood that while I have illustrated and particularly described certain apparatus and arrangement of circuits for the purpose of segregating or separately indicating the characteristics or constants of the circuits to be balanced, I do not wish to be restricted thereby, but intend to cover all modifications and arrangements which will be apparent to those skilled in the art for effecting the same result. It is also evident that I may employ the method above described in balancing or indicating the condition of electric circuits other than those employed in systems of telegraphy.

I claim as my invention, and desire to secure by Letters Patent in the United States,

1. The method of balancing a plurality of electric circuits, which consists in separately indicating the relative effects of the different constants of the circuits, and changing the values of said constants until a balance of each is indicated.

2. The method of balancing a plurality of electric circuits, which consists in segregating the effects of the different constants of the circuits, and changing the values of the constants of one circuit until a balance or equality of the constants in the circuits is indicated.

3. The method of balancing a plurality of electric circuits which consists in connecting a plurality of indicating instruments between said circuits, dephasing the currents flowing in said instruments, and adjusting the constants of the circuits until a balance is indicated.

4. The method of balancing a plurality of electric circuits which consists in connecting a plurality of indicating instruments of the electro-dynamic type between said circuits, dephasing the currents flowing in the movable elements of said instruments, and adjusting the constants of the circuits until a balance is indicated.

5. The method of balancing a plurality of electric circuits which consists in affecting a plurality of indicating instruments by currents flowing in said circuits, causing said instruments to respond to different constants of said circuits, and adjusting the constants of one circuit until a balance or equality is indicated by each instrument.

6. The method of balancing a plurality of electric circuits which consists in affecting a plurality of indicating instruments by currents flowing in said circuits, causing one of said instruments to respond to changes in the value of the currents of said circuits, and another instrument to respond to changes in the phase relation of the currents in said circuits, and adjusting the constants of one cir-

cuit until a balance or equality is indicated by each instrument.

7. The method of balancing a plurality of electric circuits which consists in affecting a plurality of indicating instruments by currents flowing in said circuits, causing one of said instruments to respond to changes in the relative resistance of said circuits and another instrument to respond to changes in the capacity or condenser effect of said circuits, and adjusting the constants of one circuit until a balance or equality is indicated by each instrument.

8. In a system of telegraphy, means for indicating a balance of the constants of the circuits, comprising a plurality of indicating instruments connected between said circuits; and means for displacing the phase of the currents flowing in the instruments.

9. In a system of telegraphy, means for indicating a balance of the constants of the circuits, comprising a plurality of indicating instruments connected between said circuits; means for causing one of said instruments to take a current in phase with the potential across said circuits and means for causing another instrument to take a current in quadrature thereto.

10. In a system of telegraphy, means for indicating a balance of the constants of the circuits, comprising a plurality of indicating instruments connected between said circuits; and means in said circuits whereby one instrument has a maximum sensibility and another instrument a minimum sensibility.

11. In a system of telegraphy, means for indicating a balance of the constants of the circuits, comprising a plurality of indicating instruments connected between said circuits; means for causing one instrument to indicate changes in the relative resistance of said circuits and means for causing another instrument to indicate changes in the phase relation of currents in said circuits.

12. In a system of duplex telegraphy having real and artificial lines, the combination of a pair of indicating instruments of the electro-dynamometer type having their movable elements connected across said lines, means for causing one instrument to indicate changes in the relative resistance of said lines, and means for causing the other instrument to indicate changes in the relative capacity or condenser effects of said lines.

13. In a system of duplex telegraphy having real and artificial lines, the combination of a pair of indicating instruments of the electro-dynamometer type having their movable elements connected across said lines, means for causing one instrument to indicate changes in the relative resistance of said lines, means for causing the other instrument to indicate changes in the relative capacity or condenser effects of said lines, and

means for adjusting the resistance and capacity of said artificial line.

14. In a system of duplex telegraphy having real and artificial lines, the combination 5 of a pair of indicating instruments of the electro-dynamometer type having their movable elements connected across said lines, one of said instruments having a field excited by the current of said system and the other 10 instrument having a permanently magnetized field, and means for adjusting the resistance and capacity of said lines.

15. In a system of duplex telegraphy having real and artificial lines, the combination 15 of a pair of indicating instruments of the

electro-dynamometer type having their movable elements connected across said lines, one of said instruments having a field excited by the current of said system and the other instrument having a permanently magnetized field, and means for periodically connecting and disconnecting the circuit of the movable elements. 20

In testimony whereof, I affix my signature, in presence of two witnesses.

LOUIS M. POTTS.
